UNITED STATES PATENT OFFICE.

THOMAS J. CULLEN, OF JERSEY CITY, NEW JERSEY.

STEAM-HEATING APPARATUS.

1,124,301.

Specification of Letters Patent.

Patented Jan. 12, 1915.

Application filed April 24, 1914. Serial No. 834,151.

To all whom it may concern:

Be it known that I, THOMAS J. CULLEN, a citizen of the United States of America, residing at Jersey City, in the county of 5 Hudson and State of New Jersey, have invented certain new and useful Improvements in Steam-Heating Apparatus, of which the following is a specification.

The present invention relates to improvements in steam heating apparatus, especially 10 designed for heating dwellings, apartments, and other places by the radiation of heat conveyed through the steam, and utilized through the usual steam radiators of the 15 tapped top and bottom type.

The object of the invention is to provide a steam heating system which is economical in the consumption of fuel, is efficient in conveying the radiating heat, and which is 20 simple in arrangement, accurately controlled and regulated, and which is proficient in deriving from the vapor, the best results obtainable in a heating system of this character.

25 The invention consists in certain novel combinations and arrangements of parts in connection with the steam boiler, by means of which a vacuum is created throughout the system, so that the heating fluid, or steam, 30 may be conveyed to the several fixtures without obstruction, and in order to avoid and eliminate many objectionable features found in heating systems of this character which do not have an efficient vacuum or suction 35 apparatus.

In the accompanying drawings I have 40 illustrated one complete example of the physical embodiment of my invention constructed according to the best mode I have so far devised for the practical application 45 of the principles of the invention.

Figure 1 shows a steam heating system complete, one fixture or radiator being illustrated. Fig. 2 is a sectional vertical view 45 of the regulator and indicator of the system, showing the condition of steam and water through the complete system. Fig. 3 is an enlarged vertical sectional view of a regulating valve for the heat in a radiator, 50 and designed to prevent short circuit, and to reduce or choke off the live steam from returning through the suction or vacuum pipe. Fig. 4 is an enlarged detail view of the valve plug of Fig. 3. Fig. 5 is a trans- 55 verse sectional view of Fig. 4, on line 5-5.

In the preferred embodiment of my invention I employ a boiler 1, of well known type, and the furnace of this boiler is designed to create the vacuum or suction which forms a dominant feature of my invention. 60 The boiler furnace is provided with a usual type of air draft door 2, and the chimney or smoke flue 3 is provided with a casing 4 at its juncture with the boiler 1 showing a second hinged air door 5 similar to, but of 65 smaller dimensions than the door 2. The door 2 is designed to permit the introduction of air to the fuel in the furnace, and the door 5 is designed to retard the draft through the flue 3, and these doors are operated through regulating means as will be 70 described.

The main steam pipe 6 is illustrated as rising from the boiler 1, and extends to the right and left in Fig. 1, so that it may 75 make a complete circuit, and has the radiator supply pipes as 7 extending therefrom. The supply pipe 7 as shown in Fig. 1, is connected to the radiator 8, and has a quick acting controlling valve 9 adjacent the radiator 8, to regulate the supply of steam to 80 the radiator.

The water of condensation in the lower head 13 may return through the valve 9 and pipe 7 into pipe 6, and thence by pipe 85 14 to the right in Fig. 1, such water may return through the horizontal pipe 15 to the water space in the boiler.

Into the upper head 16 of the radiator a suction pipe 17 is extended and this pipe is 90 provided with exit-holes or slits 18 which open into the radiator, and are adapted to conduct therefrom the air or gases, and they are conveyed through the pipe 19 by suction to the return pipe 20 and from the return 95 pipe 20 by means of the vertical pipe 21. This pipe 21 extends through a portion of the furnace of the boiler where it is heated by the gases of combustion in the furnace, and emerges at the opposite side of the 100 boiler and then passes through the casing 4 and extends a suitable distance up into the smoke flue 3. This arrangement of the pipe 21 and its passage through a heated portion of the furnace 1 terminating in the flue 3 105 whereby a draft is caused from the pipe into the flue, causes a suction from the radiator 8 through pipe 19, return pipe 20 and 21, and thence up into the flue 3, thus removing all obstruction out of the path of 110

the live steam passing through the radiator, and tending to create a suction in these parts so that the steam may pass to the radiator and thereby heat the room.

5 In Fig. 1, the terminal of the pipe 21 is indicated, and it will of course be understood that the flue 3, which is shown as broken, will, in actual practice, extend up into a chimney or stack beyond the end of the pipe 21.

10 In Fig. 1 I have illustrated two cooling tanks as 22 and 23 through which coils 24 and 25 of the return pipe 20, are extended, and these tanks are adapted to receive cold air as through the flue 26, and are provided with the vent 27. These cooling tanks are designed to prevent the passage through the return pipe, of live steam, inasmuch as they will condense any returning vapor, and the 15 moisture of condensation from the coils will be conveyed back to the boiler, from the coil 24 by means of a vertical pipe 27, and from the coil 25 by means of an elbow 28 condensation will pass to an equalizing vessel 29 which is in communication with the water space of the boiler through the vertical pipe 30 and the horizontal pipe 31 as shown in Fig. 1.

20 Referring to Fig. 3, the screw plug or valve 32 is designed to regulate the passage of the air or gas from the radiator, and this screw plug or valve is of peculiar construction. It is formed in its sides with a pair of slots 33—33 which at one end of the plug, have a maximum depth of almost one half the diameter of the plug, and which diminishes to nothing at the opposite end of the plug. This plug 32 is incased in the valve casing or fixture 34 located at the head of the pipe 19, and the valve casing is in communication through the plug 32 with the outlet or vacuum pipe 17 in the top of the radiator. Within the casing 34 a grid or 25 perforated partition 35 is provided to prevent the loss of the plug 32 as it is adjusted within the casing. A screw plug 36 threaded into a bushing 37 in the casing 34 may be removed and access may be had to the plug 32 by means of a screw driver, so 30 that the plug may be turned to the right to reduce the passage of gas through the casing, or to the left to increase the passage of the gas through the casing. By turning the plug in either direction, it will be understood that the supply of dry steam to the 35 radiator is regulated, and in this manner the maximum flow of steam through the radiator may be determined. It will, of course, be understood that the valve 9 may 40 be employed to entirely shut off the steam from the radiator, and thereby regulate the admission of steam to the radiator, but the action of the valve 9 will be determined by the position of the screw plug 32 as will be 45 understood.

The equalizing and draft regulating device inclosed in the vessel 29 is designed to adjust the two doors 2 and 5. This vessel or tank 29 is adapted to receive moisture from condensation through the pipe 28 which has its lower end 38 submerged below the water line in the tank and in Fig. 1, it will be noted that the high water line of the gage 39, is the same as the low water line of the boiler in the tank 29. Steam from the main pipe 6 is introduced into the tank 29 through the connecting pipe 40, and this pipe 40 has a downward extension 41 for the water of condensation to pass to the horizontal pipe 31.

50 Within the tank 29 the steam pipe 40 connects with the casing 42 in which the safety valve 43 is adapted to operate, and an outlet elbow 44 opens within the tank 29 from the casing 42, and in this manner steam pressure is permitted to enter the tank 29. In the present construction however should the boiler blow off water instead of steam the water will simply run into the receiver and back into the boiler instead of overflowing into the room in which the furnace is situated. Within the tank 29 a float 45 is suspended by means of the stem 46 and the pivoted slotted link 47. This link 47 is pivoted at 48 to the stem 46, and at 49 is pivoted to the inner wall of the tank 29. A second link 50 which is pivoted at 49' is also connected with the link 47 by means of a vertically arranged link 50', and this link 50 is adapted to engage a member 54' which is adjustable on the valve stem 51. This member 54' is a metallic bar, bent so that its shank will project through one of the perforations 51' in the stem 51, and an arm 54a will be suspended at the side of the stem 51, in the path of movement of the link 50. A chain 52 is attached at 53 to the link 47. Thus, when the float 45 is lifted by the water, the link 50 through the described connection, is lifted until it engages the arm 54a of the member 54', and a continued rising movement of the ball lifts the valve 43 from its seat as will be understood.

55 In Fig. 1, it will be seen that this chain passes over suitable pulleys 53, and that the chain branches into two sections 54 and 55, the former having a rocking arm 56, and attached to the door 5, and the latter attached to the door 2. In Fig. 1, the draft door is open and the draft retarding door 5 is closed, so that the draft is on in the furnace. A water glass 56' is located outside of the tank 29, and in conjunction therewith a gage plate 57 is used which indicates pressure up to twenty ounces.

60 There are several meritorious features in connection with my invention, among which are the automatic regulating device contained in the tank 29 by means of which the two doors, 2 and 5, are controlled to increase 65

the draft and consequently increase the steam pressure in the boiler, or decrease the draft, by closing the door 2 and opening the door 5. This regulation is accomplished by the presence in the tank 29 of the water of condensation and the steam acting upon the float 45 which operates the described mechanism connected to the chains 52, 54 and 55. The pressure within the tank 10 is indicated on the scale 57, and in Fig. 1, it will be noted that the highest point of the water glass 39 on the boiler is on a level with the lowest point of the water line in the tank 29.

15 The cooling tanks 22 and 23 also aid materially in providing an efficient system, and by means of these tanks to which cold air from outside the house is drawn, any steam that may escape through the valve 20 casing 34 finds its way through return pipe 19, will be condensed and thus prevented from returning through pipe 21.

25 A further meritorious feature of the invention resides in the arrangement of the pipe 21 as it passes through the boiler furnace and into the smoke flue 3. The heat from the furnace causes a circulation of air in the pipe 21, the heated air passing up through the flue 3 and thus tending to cause 30 a vacuum through the pipe 21, and this vacuum insures a movement of air and gas through the pipe 19 from the radiator 8, and in this manner all of the radiators are cleared of air and gases, so that the steam 35 may enter and reach all parts of the radiator. In this manner the heat is uniformly distributed throughout the system, and water of condensation will be drained back through the pipe 7 into pipe 6, and then into

the water space of the boiler as before described. 40

Having thus fully described my invention, what I claim as new and desire to secure by Letters Patent, is:—

1. The combination with a boiler, its furnace, and smoke flue, of a steam radiator, a steam pipe communicating with the boiler and radiator, a return pipe from the radiator extending through the boiler furnace, where it is heated to cause circulation of air 45 therein, and into the smoke flue, and means for controlling the passage of gases from the radiator to the return pipe comprising a screw plug forming a valve and having longitudinal tapered slots therein to control 50 the passage therethrough of gases from the radiator. 55

2. The combination with a boiler, its furnace, and smoke flue, of a steam radiator, a steam pipe communicating with the boiler 60 and radiator, a return pipe from the radiator extending through the boiler furnace, where it is heated to cause circulation of air therein, and into the smoke flue, a condensing coil in the return pipe, and means 65 for controlling the passage of gases from the radiator to the return pipe comprising a screw plug forming a valve and having longitudinal tapered slots therein to control 70 the passage therethrough of gases from the radiator.

In testimony whereof I affix my signature in presence of two witnesses.

THOMAS J. CULLEN.
